[57] **CLAIM**

The ornamental design for a combined grater/shredder/slicer and container, as shown.

DESCRIPTION

FIG. 1 is a top, front, right side perspective view of a combined grater/shredder/slicer and container showing my new design;

FIG. 2 is a right side elevational view thereof;

FIG. 3 is a rear elevational view thereof;

FIG. 4 is a bottom plan view thereof;

FIG. 5 is an exploded, reduced scale perspective view thereof;

FIG. 6 is an exploded, reduced scale perspective view thereof;

FIG. 7 is an exploded, reduced scale perspective view thereof;

FIG. 8 is a top, front, right side perspective view of an alternative embodiment of FIG. 1;

FIG. 9 is a right side elevational view of FIG. 8;

FIG. 10 is a rear elevational view of FIG. 8;

FIG. 11 is a bottom plan view of FIG. 8;

FIG. 12 is an exploded, reduced scale perspective view of FIG. 8;

FIG. 13 is an exploded, reduced scale perspective view of FIG. 8; and,

FIG. 14 is an exploded, reduced scale perspective view of FIG. 8.
